CONTAINER FILLING DEVICE

Peter Darabaris, East Paterson, N. J.

Application October 1, 1947, Serial No. 777,244

4 Claims. (Cl. 226—19)

1

This invention relates to filling devices for filling liquid containers, and aims to provide certain new and useful improvements whereby the utility and efficiency of the device is substantially enhanced.

Another object of the invention is the provision of an improved device of the class mentioned, which is constructed so that the flow of water or liquid will be automatically stopped when the desired level of the liquid is reached, so that the liquid level in a container such as, for example, a storage battery, remains at the predetermined height after the level has been raised to that height.

A further object of the invention is the provision of a visible indicator to indicate to the operator that the liquid is flowing through the device.

The above as well as additional and more detailed objects will become apparent in the following description, wherein characters of reference refer to like-numbered parts in the accompanying drawing. It is to be understood that the drawing is intended for the purpose of illustration only, and that it is neither desired nor intended to limit the invention to any or all of the specific details of construction shown, excepting insofar as they may be essential to the invention.

Referring in detail to the drawing,

Fig. 1 is a central longitudinal sectional view of the battery filling device in position for use, applied to the cell of a storage battery, the latter being shown fragmentarily in section.

Fig. 2 is a sectional view taken on the line 2—2 of Fig. 1.

Fig. 3 is a sectional view taken on the line 3—3 of Fig. 1.

Fig. 4 is a sectional view taken on the line 4—4 of Fig. 1.

Fig. 5 is a fragmentary plan view of the device.

Referring in detail to the drawing, the numeral 10 indicates a housing of any suitable material such as, for example, hard rubber or plastic, which may be molded in one piece. A neck 11 extends upward at an angle from the housing 10, intermediate the height of the latter. The upper portion of the housing 10, indicated at 10a and positioned above the neck 11, is of substantially the ovate conformation shown in Figs. 2 and 5; the lower portion 10b of the housing 10, below the neck 11, is of substantially the circular conformation shown in Figs. 3 and 4.

The neck 11 is provided with two spaced non-

2

axial passages, one above the other, indicated at 12 and 13, the former communicating with the bottom of a well 14 formed in the housing 10a, and the latter communicating with the top of an axial bore 15 extending upward into the housing 10b.

On each side of an imaginary plane passed through the axis of the neck 11 and the axis of the housing 10b, that is, the plane of the paper in Fig. 1, a substantially crescent-shaped or nearly semi-annular passage 16 is cut down through the housing 10 from the base of the neck 11 to the lower end of the housing. In addition, a semi-annular passage 17 is cut down partway through the housing 10a, to the left of a vertical plane passed through the axis of the housing 10b down into the paper at right angles to the paper, Fig. 2. The two ends of the semi-annulus terminate at 16a, 16b, Fig. 2. The lower extremity or base of the passage 17 is shown at 18. A small portion of the upper extremity of the housing 10 is dished out, thereby providing a space 19 between the cover 20 and the floor 21 and providing a flange 22 surrounding this dished-out space. It is thus apparent that, assuming the well 14 to be full of water and that the level therein rises to flow over the floor 21, the water will then fall down into the passage 17. The ends of each of the semi-annuli of the passages 16 are shown in Fig. 2 at 16a and 16b. It is thus apparent that the passage 17 overlaps both passages 16; hence, the water will flow from the passage 17 down into both passages 16.

The bore 15 is reduced intermediate its height to provide an internal flange 23. A piston 24 is slidably mounted in the lower end of the bore 15, and is normally urged downward by a coiled spring positioned between the flange 23 and the top of the piston, shown at 24a. The piston has a channel 25 extending downward partway through the top thereof, which channel turns angularly outward at 26 and passes through the side of the piston at 27.

A vertical slot or groove 28 is provided in one side of the piston 24, in which one end of a pin 29 which is imbedded in the housing 10, registers, and the upper and lower extremities of this groove serve as limit stops to the longitudinal movement of the piston 24.

A passage 30 is cut, substantially parallel with the passage 26, through the wall of the housing 10, terminating in a vertical groove 35 extending from the outer end of the passage 30 to the lower extremity of the housing 10. A storage battery 36 is shown fragmentarily at 32, having the cell 33

in which the battery plates are shown at 34. A liquid container is shown at 36, and this may be a bulb or any other container; it is provided with a flange 37 by means of which it is adapted to be connected to the free end of the neck 11.

The cover 20 has an opening 38 therethrough at an angle, and secured in said opening is the upper end of a perforated tube 39 whose lower end is open. The upper end of the tube 39 is closed by a transparent cover or closure 40. A ball float 41 which may be coated with luminous material, is loosely mounted in the tube 39, but, owing to the position of the open end of the tube against the wall of the well 14, the ball cannot fall out of the tube.

Normally, as is apparent, the spring 24a will urge the piston 15 outward to its limit, whence the passages 26 and 30 will become disaligned; this position is not shown in the drawing. When the device is applied to a storage battery, however, by way of example, as shown in Fig. 1, with the tip of the piston in contact with one or more plates 34, and the device is pressed down or permitted to move down by its own weight, the piston will move into the housing 10 into the position shown in Fig. 1, with the openings 26 and 30 aligned and thereby providing an air inlet into the bore 15. Air will thus pass into the container 36 through the passage 13, at the same time as water passes from the container 36 through the passage 12 into the well 14. As previously described, the water, upon overflowing from the well 14, will pass down through the passages 16, and hence it will leave the housing 10 at the bottom and enter the cell 33. Upon rising of the level of water in the cell to a position level with the top of the mouth of the passage 30, the air inlet supply will be shut off and hence no more water will be able to leave the container. Thus the possibility of passing too much water into the cell is eliminated. When the device is lifted from the filled cell, the piston 24 will again be expelled, thus also preventing the water still in the housing 10 from passing out of the housing.

As the well 14 fills at the beginning of the operation just described, the ball 41 will rise to the top of the tube 39 and will be visible through the window 40, indicating that the device is functioning and that water is flowing properly. It has been found by experience that, when the air supply is cut off as described, a suction is provided in the air passage 26, 25, 15, and 11, and the container 36, which is sufficient to draw all or a good part of the water remaining in the housing 10 back into the container, and that some of the water then flows back into the well 14 to a depth sufficient to close the trap-like bottom of the well between the latter and the lower end of the passage 12.

Obviously, modifications in form and structure may be made without departing from the spirit or scope of the invention.

I claim:

1. A vessel-filling device adapted to fill to a predetermined level a vessel having a support po-

sitioned below the rim of the vessel and below said level, comprising a housing adapted to be used in upright position, said housing having a neck extending therefrom intermediate the height of the housing, said neck having two spaced longitudinal passages therethrough one above the other, said housing having a bore extending upward thereinto and communicating at the top with the lower of said neck passages, said housing having a well cut into the top thereof and communicating at the bottom of said well with the upper of said neck passages, said housing having a substantially semi-annular passage extending down thereinto from the top of said well, spaced openings extending upward into said housing from the bottom and communicating at the top with said semi-annular passage, the top of said housing having a flange extending upward therefrom, a cover mounted on said flange and spaced from said top of the housing, a liquid container mounted on the end of said neck, said bore having an internal flange intermediate its length, a piston slidably mounted in said bore below said last-named flange and having its lower end projecting from said bore, means normally urging said piston outward from said bore, limit stops to the longitudinal movement of said piston, said piston having a channel extending downward thereinto and turning angularly at its lower end through one side of the piston, said housing having a passage therethrough at its lower end adapted when said piston lies in its extreme upper position to align with said lower end of said piston channel and to be disaligned when said piston lies in its extreme lower position, said piston upon mounting the device in said vessel with said piston resting on said support and pressing the device downward being raised to its said extreme upper position.

2. The device set forth in claim 1, having visual indicating means actuated by the rising of liquid in said well to overflow said well.

3. The device set forth in claim 1, said limit stops comprising a longitudinal slot in said piston, a pin rigid in said housing and projecting into said slot.

4. The device set forth in claim 1, said cap having an opening therethrough, a tube extending downward from said opening and having a float loosely mounted therein, the upper end of said tube having a transparent closure thereon, the lower end of said tube being open.

PETER DARABARIS.
